SHORT WAVE RADIATION

Walter Dällenbach, Berlin-Charlottenburg, Germany, assignor to N. V. Machinerie-en Apparaten Fabrieken "Meaf", Utrecht, Netherlands

Application June 26, 1933, Serial No. 677,733
In Germany July 6, 1932

5 Claims. (CL 250—11)

It is difficult when communicating with ultra-short waves to cause sender and receiver to operate selectively so that neither an undesired reception of foreign stations by one's own receiver nor the unauthorized reception of one's own transmissions by third persons or their interference is possible. In order to obtain high selectivity it has been proposed to send the sender on a very narrow and constant wave band and to provide the receiver with the best possible screening means.

In order to render messages inaccessible to unauthorized persons during the transmission of intelligence, it has been proposed to build senders for a very narrow wave range and thus make reception more difficult. Furthermore, arrangements have been proposed which, as far as possible, permit the bunching together of the rays in one direction to prevent, or render difficult, reception in other directions, but such arrangements fail to give satisfaction in view of the increasing use of receiving devices.

By producing a wave of peculiar structure the invention provides a means for rendering reception by unauthorized persons extraordinarily difficult.

An electromagnetic oscillator, such as an electric or magnetic dipole, has an axis of symmetry in which it practically does not radiate at all. The rays emitted by it extend chiefly vertically to the axis in the equatorial plane and decrease in the direction towards the pole in the square of the cosine of the geographical latitude. To permit utilization of the directional radiation, an emitter of this type has always been arranged so that its axis was adjusted vertically to the direction of propagation into which the rays were to be thrown. In wireless telegraphy, the axis of symmetry of an aerial is, therefore, as a rule, oriented vertically to the earth's surface. Ultra-short electric waves in the sphere of centimeter and decimeter waves permit concentration of radiation for instance by means of reflectors. Applying the fundamental principle mentioned above, when such reflectors were used, the arrangement of the axis of symmetry of the emitter relative to the direction of propagation of the rays has been retained, so that even in case of a reflector, the axis of symmetry is adjusted vertically to the direction of propagation.

It has been found, however, that an essential advance may be made by arranging the axis of symmetry of the emitter in a different way if a reflector is used.

By way of example, the invention is illustrated

in the accompanying drawing, in which Figures 1, 2 and 3 are diagrams of embodiments of the invention.

Fig. 1 shows an arrangement having an electric dipole represented by the linear oscillator ST which coincides with the axis X—X of a parabolic mirror having coinciding axes of rotation and symmetry, the focus of the mirror being at F and the apex at A. The direction of propagation of the rays emitted by the mirror also coincides with the direction X—X and thus with the axis of the linear oscillator ST.

Such an arrangement produces radiation which differs in essential points from the known arrangements for producing directional waves, and further explanation will be given with reference to the example shown in Fig. 1. Corresponding to the direction diagram of the emitter indicated, the radiated energy will preferably be emitted in the equatorial plane MNF while only very slight portions of the rays will fall into the angular space PFQ where the radiation leaves the mirror without being reflected and concentrated. This means that stray radiation falling, in the usual arrangements, in the angular space PFQ is practically eliminated in the arrangement according to Fig. 1, which produces greater concentration of the rays in the interest of secrecy and in order to avoid interference with adjacent stations. Simultaneously, the new arrangement makes it possible to reflect practically the entire radiated energy emitted by the sender ST on the mirror in the direction X—X, which involves a considerable saving in expenditure of energy or a higher field intensity at the point of reception.

However, the new arrangement affords another advantage. The energy emitted by the radiator leaves the mirror without passing over the radiator again, as is always the case with arrangements in which the emitter is disposed vertically to the mirror axis. In an arrangement of the hitherto customary type a coupling will therefore be produced between the mirror and emitter, which makes it necessary to choose the focal distance of the mirror at a certain ratio to the wave length, whereas in the arrangement shown in Fig. 1 such a coupling between reflectors and emitters is not required, so that the focal distance of the mirror may be chosen independently from the wave length.

The new arrangement further possesses a special feature by supplying a ray of a certain structure. The intensity of radiation is greatest on a cylindrical face having the axis X—X and the circle above the diameter MN as cross section,

and radially decreases from this surface both outwardly and inwardly. The magnetic lines of force are circles about the axis X—X, but the electric lines of force extend as cross sectional lines of torus faces which also have the axis of symmetry X—X for their axis of rotation. In Fig. 3, this is shown in perspective, the general arrangement being the same as in Fig. 1. The points of greatest intensity of radiation are located on the circular cylinder constructed above the diameter MN with the axis X—X. A section made vertically to the axis of this circular cylinder represents a magnetic line of force H. The intensity of the magnetic field strength along such a line of force H varies for a certain length of time periodically in the direction of the axis X—X in so far as the field strength, dropping from maximum to zero, attains after half a wave length the maximum value in opposite direction. The electric field strength for points near the circular cylinder of maximum intensity of radiation is chiefly radially directed, i. e., in distances of half a wave length with maximum intensity radially inwardly or outwardly. At distances amounting to a few wave lengths from the cross sectional surface MN the maxima of magnetic field strength will coincide with the maxima of electric field strength. Magnetic and electric field strengths are, therefore, arranged relative to one another as indicated by the vectors E and H. Vertically to the latter the vector U of energy flow points in the direction X—X, so that the electric lines of force extend in the meridional planes through the axis X—X and form closed curves K, as indicated for the meridional plane by the point M.

The novel arrangement of the emitter relative to the mirror thus permits the formation of a tube-like ray which possess the advantage of extremely sharp concentration and which permits reception by another station only if transmitting and receiving stations are accurately adjusted to one another.

It is evident that the effect described can be attained also in a manner differing from the arrangement according to Fig. 1. For example, Fig. 2 shows an arrangement in which the electric dipole is replaced by a magnetic dipole in the form of a circular conductor disposed in the focus coaxially with the mirror and traversed by a high frequency current. This arrangement shows the lines of force disposed in a manner coinciding with that of Fig. 3, provided the magnetic lines of force are substituted for the electric lines.

The arrangement described in connection with a transmitter can be used also for a mirror system intended for reception, provided that the ray to be received possesses the tube-like form mentioned above, since only in this case will an emitter adjusted with its axis of symmetry to the direction of propagation respond. The formation of the beam according to the invention compared with an ordinary plane may therefore be likened to a safety key while the plane wave represents an ordinary key. The highly complicated structure of the beam compared with a plane wave requires a corresponding adaptation of the reception to the transmitted wave and thus protects the receiving station to a very high degree against responding due to any electromagnetic interferences of other kinds, so that reception is rendered free from interferences.

Rays of the kind described are particularly suited also for electric train protection.

Furthermore, the use of structured electromagnetic rays with axis of rotation or a plane of symmetry is advisable also for all position finding work requiring great accuracy, such as direction findings for fixing routes for aircraft and hydro-aeroplanes or the like.

The emitters disposed in the mirror may be tubes or aerials connected with tubes by high frequency circuits. Instead of a parabolic mirror having coinciding axes of rotation and symmetry a cylindrical mirror disclosing a parabola in cross section may be employed. If in this arrangement the axis of the dipole is disposed again in the direction of propagation of the ray coming from the mirror, the wave leaving the mirror is no longer rotation-symmetrical but has a plane of symmetry, i. e., the plane determined by the parabola and the direction of the surface lines of the cylinder.

In the customary arrangement, for instance, the axis of the electric dipole is disposed vertically in the focus of a parabolic mirror adjusted with horizontal axis. The beam leaving the mirror is then, over the entire cross section, approximately linearly polarized in such a way that at all points of the cross section of the beam the electric field strength is directed approximately vertically and the magnetic field strength approximately horizontally, so that the beam corresponds accurately to a plane wave limited as to space.

On the other hand, if, according to the invention, the axis of the dipole lies in the axis of the parabolic mirror, that is, is disposed in the direction of propagation of the ray, a tube-like ray will be produced which completely deviates from the plane wave. It is as impossible to change the structure of this ray to that of a plane wave by steady transformation as it is to convert a torus surface to a spherical one by steady deformation.

If instead of a parabolic mirror having coinciding axes of symmetry and rotation a parabolic mirror is chosen whose cross section, vertically to the axis of symmetry, will produce an ellipse, the cross section of the tubular ray will also be elliptically deformed and, if the major axis of the elliptical cross section is extended to infinity, pass into the fall of the ray with the axis of symmetry.

I claim:

1. A system for the transmission of messages by short electric waves, consisting of a sender and a receiver, the sender comprising a rotary-symmetrical reflector and an electric dipole, the receiver comprising a rotary-symmetrical reflector and an electric dipole, each dipole arranged in the focus of the associated reflector and extending in the direction of the axis of the reflector, whereby the sender produces a tubular parallel radiation field, the receiver receiving this tubular radiation field.

2. A system for the transmission of messages by short electric waves, consisting of a sender and a receiver, the sender comprising a rotary-symmetrical reflector and a magnetic dipole, the receiver comprising a rotary-symmetrical reflector and a magnetic dipole, each magnetic dipole arranged in the focus of the associated reflector and its axis of symmetry coinciding with the axis of symmetry of the reflector, whereby the sender produces a tubular radiation field, the receiver receiving this tubular radiation field.

3. A system for transmitting messages with short electric waves, consisting of a sender and a receiver, the sender containing a rotary-sym-

- metrical reflector and a dipole, the receiver containing a rotary-symmetrical reflector and a dipole, each dipole being disposed in the focal point of the associated reflector, and its axis of symmetry coinciding with the axis of symmetry of the reflector, whereby the sender generates a tubular parallel radiating field, the receiver receives this tubular radiating field.
4. A system for transmitting messages through short electric waves, consisting of a sender and a receiver, the sender comprising a reflector and an oscillator, the receiver comprising a reflector corresponding to the reflector of the sender and an oscillator, each oscillator disposed in the focal point of the reflector, its axis coinciding with the direction of the emitted radiation, whereby the sender produces a non-homogeneous parallel radiation field and substantially the entire cross section of the emitted radiation beam is taken
5. A system for transmitting messages through short electric waves, consisting of a sender and a receiver, the sender comprising a reflector and an oscillator, the receiver comprising a reflector corresponding to the reflector of the sender and an oscillator, which is disposed in the reflector of the receiver in the same position as the oscillator of the sender in the reflector of the sender, each oscillator disposed in the focal point of the reflector, its axis coinciding with the direction of the emitted radiation, whereby the sender produces a non-homogeneous, parallel radiation field and substantially the entire cross section of the emitted radiation beam is taken up by the receiver practically over its entire cross section.

up by the receiver practically over its entire cross section.

5. A system for transmitting messages through short electric waves, consisting of a sender and a receiver, the sender comprising a reflector and an oscillator, the receiver comprising a reflector corresponding to the reflector of the sender and an oscillator, which is disposed in the reflector of the receiver in the same position as the oscillator of the sender in the reflector of the sender, each oscillator disposed in the focal point of the reflector, its axis coinciding with the direction of the emitted radiation, whereby the sender produces a non-homogeneous, parallel radiation field and substantially the entire cross section of the emitted radiation beam is taken up by the receiver practically over its entire cross section.
